(57) **CLAIM**

The ornamental design for a display panel with animated graphical user interface as shown and described.

DESCRIPTION

The file of this patent contains at least one drawing/photograph executed in color. Copies of this patent with color drawing(s)/photograph(s) will be provided by the Office upon request and payment of the necessary fee.

1. Display panel with animated graphical user interface
1.1 : shows a display panel with animated graphical user interface showing the first image of my new design;
1.2 : shows a second image thereof; and
1.3 : shows a third image thereof.

The appearance of the animated graphical user interface sequentially transitions between the images shown in 1.1 through 1.3. The process or period in which one image transitions to another image forms no part of the claimed design.

The outermost broken line rectangle in each figure illustrates the display panel. All remaining broken, including all dash-dot broken lines and all dot-dot broken lines, illustrate portions of the graphical user interface. None of the broken lines form part of the claimed design.
